UNITED STATES PATENT OFFICE

WILLIAM S. RICE, OF WASHINGTON, DISTRICT OF COLUMBIA

METHOD FOR THE PRODUCTION OF DENTURES

Application filed May 28, 1928. Serial No. 281,278.

(GRANTED UNDER THE ACT OF MARCH 3, 1883, AS AMENDED APRIL 30, 1928; 370 O. G. 757)

This invention described herein may be manufactured and used by or for the Government for governmental purposes, without the payment to me of any royalty thereon.

5 This invention relates to a method for improving the present processes in prosthetic dentistry for effecting various forms of artificial restoration of the oral cavity, more especially it is directed to a method for the 10 production of full and partial plates, bridges, inlays, dental splints, obturators, etc., and the models necessary to their construction.

15 One of the objects of this invention is the provision of nonporous, noncompressible surfaces between which the model may be invested and the denture, which replaces it, vulcanized or otherwise treated and thus by the 20 elimination of expansion and warping, producing a denture which will conform to the contour of the gums and hard palate to the minutest details.

25 Another object of this invention is to provide means for embedding the teeth in metal in the investment flask thus holding them solidly in position for packing and vulcanization, curing or otherwise hardening the base 30 plate material.

35 Other objects of this invention are to materially lessen both time and labor in the production of dentures and other restorative forms by effecting a reduction in the amount of grinding and polishing necessary for finishing and to provide metallic separating layers between the upper and lower sections of the flask.

40 With these and other objects in view this invention consists in certain novel details of construction, combination and arrangement 45 of parts to be more particularly hereinafter set forth and claimed.

Briefly stated, this invention consists in an 45 improved method for producing models, dentures, inlays, etc., by the use of metallically surfaced models or metallically lined molds between the hard smooth surfaces of which the plastic model is invested and the plastic denture vulcanized or cured to form the finished denture or other artificial restoration.

50 Referring more particularly to the accom-

panying drawings in which corresponding parts are indicated by similar reference characters:

Fig. 1 is a sectionized isometric view of an impression tray with wax or plaster impression contained therein. 55

Fig. 2 is a sectionized isometric view of an impression tray and impression material contained therein, the impression cavity being coated with a metallic lining. 60

Fig. 3 is a partially sectionized elevation of an upper and lower full denture mounted on an articulator. 65

Fig. 4 is a partially sectionized perspective view of upper model shown in Fig. 3, mounted in the lower section of an investment flask. 65

Fig. 5 is a partially sectionized perspective view showing the upper mold coated with metal and mounted in the investment flask. 70

Fig. 6 is a sectionized elevation showing the upper model invested in a closed flask for vulcanizing, curing, molding or casting. 75

The customary method of making vulcanite dentures involves the paramount features to wit: taking the impression, pouring the plaster casts, mounting casts on the articulator, building the wax models, investing, packing and then vulcanizing. 75

In the usual method the plaster cast is made by pouring plaster directly into the impression. This gives a plaster model, or cast of the patient's gums on which the wax model denture is built. This model denture is invested entirely in plaster, immersed in warm water and after the evacuation of the wax, rubber is packed in the plaster mold and vulcanized. 80

The porosity of the plaster causes adhesion of the vulcanite and the compressibility of the plaster and uneven expansion thereof causes expansion and warping of the denture. The result is rough vulcanite dentures which do not follow the exact contour of the patient's gums and hard palate, and which require considerable grinding and polishing to approximate a fit and to make the exterior of the denture resemble in smoothness the gums. 85

It is therefore the aim and purpose of this invention to provide a method to eliminate 100

the deleterious results caused by investing the wax model and vulcanizing the denture between surfaces as previously stated. In the description which follows it will be noted that in my improved method both investment of the model and vulcanization of the denture are accomplished in molds having metallically lined surfaces, sprayed on by a method which is outlined therein.

10 It will be noted that for the sake of brevity and clearness the materials which are used most commonly in prosthetic dentistry are referred to throughout the following description, namely, wax for the construction of the 15 base plate of the model, plaster for the molds, and rubber for vulcanization in the production of the finished denture or other restorative part. However, it is to be understood that in the application of my process it is not 20 necessary to adhere to these materials as any suitable substitutes may replace them with not only equal, but in some cases, superior results.

For example, bakelite may be used instead 25 of rubber, cement instead of plaster, etc. When bakelite is used for dentures, plaster cannot be used for molds in the ordinary dental processes, since it would be detrimental to the finished product to permit contact of 30 surfaces of bakelite against those of plaster. In my improved process plaster molds may be used for bakelite dentures as there is an intervening layer of metal between the plaster and the bakelite.

35 In the illustrated embodiment characterizing this invention, the numeral (1) Fig. 1 represents an impression tray and (2) the impression material, either wax, composition or plaster. The valley or groove (3) represents the impression made therein by the 40 gums of an edentulous patient.

In Fig. 2 is shown the impression tray, impression material and impression as shown in Fig. 1, but it will be noted that covering 45 the entire surface of the impression is a metallic coating or layer (4). This metallic layer (4) has been sprayed onto the surface by a metallic air brush similar to those used in blowing minute particles of metal on the hulls 50 of vessels until a protective coating of sufficient thickness is deposited.

The metal as it is blown on adheres to either the hull or to the surface already laid down and the thickness of the metallic layer is determined by the period of the operation and the character of spray. Preparatory to spraying the impression surface a suitable separator may be applied, then after a metallic layer of sufficient thickness has been deposited, said impression surface with its metal coating is covered with plaster and the latter built up to provide the requisite base (5). When the plaster has hardened to the desired extent and become affixed to the metallic coating, the impression material (2) is

removed and the metallically coated cast is now ready for mounting on the articulator.

A complementary cast for the lower jaw having a plaster base (5') and as above outlined, a metallic coating (4') is built, and with the aid of a bite plate (not shown) both are mounted in their proper relative positions on an articulator (6) as clearly shown in Fig. 3 of the drawings.

Upon these upper and lower metallically 75 covered casts are developed the wax dentures (7) and (7') by the ordinary process of first laying a base plate then building up the ridge and finally placing the teeth (18) in position. At the completion of the attachment of the 80 teeth and after the usual adjustments for occlusion and articulation have been made the models are removed from the articulator and placed in the flask.

In the flasking operation, the models embodying the cast with its metallic coating, plaster base (5) and wax denture (7) are placed in the lower section (8) of investment flasks (9), whereupon the flasking material is built up until its upper surface is coincident 90 with that of the upper edge section of the flask and the periphery of the wax denture, as shown in Fig. 4.

The flask sections having been prepared as defined the entire surface (11) of the plaster and of the wax model denture (7) including the teeth (18) may be covered with a thin application of a separator and coated with a metallic layer (13). The upper section (14) of the investment flask (9) is placed on top 100 of the lower section (8) as shown in Fig. 5, and filled with plaster, after which the flask is closed and immersed in warm water. On completion of investment and elimination of the wax the sections are separated, the molds 105 may be coated with a separator and packed with dental rubber, whereupon the flask is again closed and placed in the vulcanizer.

After vulcanization, the denture is removed from the flask, ground and polished in the usual manner, but since the vulcanization of the rubber has taken place between hard smooth metallic surfaces, grinding and polishing is necessary only to remove the ridges which might be formed at the line union of the flask surfaces, or small sections of metal adhering to the surface of the denture.

For making partial plates the same procedure is followed as in the case of full plates. For single plates, or single partial plates and bridge work the occluding model may be metallically coated. This provides a more solid occluding surface for manipulation on the articulator.

For inlay work an impression of the prepared cavity and either a portion of the tooth which is immediately adjacent the cavity, or the whole tooth is obtained. This impression is then coated or filled with metal, as previ- 130

ously described, until the coating is of sufficient thickness to be removed from the impression or mold without breaking.

If desired the cast which is made in this way may be backed with a plaster base as when making plate casts. This cast is an exact model of the tooth or that portion of the tooth containing the cavity. With a model of this sort the dentist has an exact metallic representation of the patient's tooth to work on in the laboratory, which manifestly facilitates handling in the subsequent laboratory operations.

In inlay work the wax model of the cavity may be coated entirely with metal except for the small opening for the pin which provides for a sprue hole. The metallic cast thus formed may be invested.

In making castings for inlay work, metallic base plates, bridge work, etc., the plastic model may be entirely coated with metal except where it is necessary for feed and vent sprues. The metal used for this purpose will necessarily be one having a high melting point. A cast thus formed may then be filled with molten metal in the usual manner, that is, by either centrifugal force or by creation of a vacuum at the vent sprues.

Dies and counter-dies for swaging metallic base plates may be constructed by spraying an appropriate metal on the impression and model and either building up the dies or counter-dies by continuing the spraying process or by mounting the surfaces on metallic or other suitable bases.

In conclusion it will be noted that the superiority of my improved method is dependent on the metallically lined molds which are used, and the ease with which they are built. Tin, which at present seems to be the most desirable metal, is extremely inexpensive, and any slight extra cost which might be incurred in the use of this method is however amply offset by the reduction in both time and labor incidental to grinding and polishing for finishing the denture.

Although in the foregoing certain elements have been described as best adapted to perform the functions allotted them, nevertheless it is to be understood that various minor changes may be resorted to within the scope of the appended claims without departing from or sacrificing any of the principles of the invention.

Having described my invention, what I claim as new and wish to secure by Letters Patent is:

1. A process for producing artificial restorations of the oral cavity, consisting in producing a metal surfaced cast, developing a model upon said cast, metallizing the exterior surface of the model, embedding the model and cast in a cementitious substance, evacuating the modelling material to provide a cavity whose internal dimensions conform to the dimen-

sional requirements of the desired restoration and perfecting the latter within said cavity.

2. A process for producing artificial restorations of the oral cavity, consisting in producing a metal surfaced cast, developing a wax denture upon the cast, metallizing the exterior surface of the model denture, embedding the model and cast in a cementitious substance, evacuating the wax material of the model to form a cavity whose internal dimensions conform to the dimensional requirements of the desired restoration and then perfecting said restoration within the cavity.

3. A process for producing artificial restorations of the oral cavity, consisting in forming a model with metallized exterior and interior surfaces, embedding the metal in a cementitious substance, evacuating the modelling material to define a metal walled cavity in the cementitious substance, the internal dimensions of which conform to the dimensional requirements of the desired restoration and completing said restoration within said cavity.

4. A process for producing artificial restorations of the oral cavity, consisting in forming a model with metallized exterior and interior surfaces, embedding the model in a cementitious substance, evacuating the modelling material to define a metal walled cavity the dimensions of which conform to the dimensional requirements of the finished restoration, filling said cavity with a restoration producing material and subjecting the latter to the temperature requisite to the finished product.

5. A process for producing artificial restorations of the oral cavity, consisting in forming a wax model denture with metallized exterior and interior surfaces, embedding the model denture in a cementitious substance, evacuating the wax modelling material to produce a metal walled cavity having the dimensional requirements of the finished restoration and filling the cavity with a restoration producing material and then subjecting the latter to temperatures requisite to the finished product.

6. A process for producing artificial restorations of the oral cavity, consisting in metal spraying an impression surface, forming a model cast therefrom, developing a model upon the cast, metal spraying the model surface upon the exterior surface, embedding the model and cast in a cementitious substance, effecting evacuation of the modelling material to produce a metal walled cavity, the dimensions of which correspond to those of the finished restoration and perfecting said restoration within said cavity.

7. A process for producing artificial restorations of the oral cavity, consisting in metal spraying an impression surface, forming a model cast therefrom, developing a

- wax model denture upon the cast, metal spraying the exterior surface of the model denture, embedding said denture in a cementitious substance, effecting evacuation of the wax modelling material to produce a metal walled cavity, the dimensions of which correspond to those of the finished restoration and then completing said restoration within the cavity. 5
- 10 8. A process for producing artificial restorations of the oral cavity, consisting in metal spraying an impression surface previously formed in molding material, treating said metallized surface with a plastic substance, 75
- 15 removing the molding material to provide a metal cast, developing a wax model denture upon the cast, spraying a metal surface upon the exterior of the model denture, effecting evacuation of the wax of the denture to 80
- 20 produce a metal walled cavity, the dimensions of which correspond to those of the finished restoration and perfecting said restoration within said cavity. 85
9. A process for producing artificial restorations of the oral cavity, consisting in forming an impression surface in modelling material, imparting a metal surface to the first mentioned surface, transferring the metal surface to a cementitious substance, 90
- 25 moving the molding material to provide a metal cast, developing a wax model denture upon the cast, metallizing the exterior of the denture, embedding the denture in a cementitious substance, effecting evacuation of the 95
- 30 wax material of the model denture to provide a metal wall cavity the dimensions of which correspond to those of the finished restoration forming material and subjecting such material to temperatures requisite to obtaining the finished restoration. 100
10. The method of producing an artificial denture involving the production of a metal wall which method comprises forming a trial denture with teeth in place, forming a rigid metallic shell conforming to the lingual side of the trial denture and teeth, forming a mold including the shell as a wall thereof, removing the trial denture leaving the teeth and shell in place, filling the mold with suitable denture material, and hardening the material to form the finished denture. 105
11. The method of producing an artificial denture involving the production of a metal mold which method comprises making a rigid metallic shell conforming exactly to the surface of the mouth, forming a trial denture with teeth in place, forming a rigid metallic shell conforming to the lingual side of the trial denture and incasing said teeth, removing the trial denture leaving the teeth rigidly held by the latter shell, placing the two shells together in matrix forming relation to provide a cavity whose internal dimensions conform to the dimensional requirements of the 110
- 115
- 120
- 125
- 130
- wanted artificial denture, filling the said matrix with suitable denture material, and hardening the material to form the finished denture. 135
